CLAIM

The ornamental design for a welder's helmet, as shown and described.

DESCRIPTION

FIG. 1 is an isometric view of a welder's helmet embodying my new design;

FIG. 2 is a front elevational view of the welder's helmet depicted in FIG. 1;

FIG. 3 is a right side elevational view of the welder's helmet, it being understood that a left side elevational view would be a mirror image of the view depicted in FIG. 3;

FIG. 4 is a rear elevational view of the welder's helmet shown in FIG. 1;

FIG. 5 is a top plan view of the welder's helmet shown in FIG. 1; and,

FIG. 6 is a bottom plan view of the welder's helmet shown in FIG. 1.

FIG. 2

FIG. 3

FIG. 4

FIG. 5

FIG. 6
